UNITED STATES PATENT OFFICE

143,965

DESIGN FOR A CHIMNEY-COWL

Thomas V. Early, Baltimore, Md., assignor of one-half to Irvin E. Brooks, Baltimore, Md.

Application April 27, 1945, Serial No. 119,280

Term of patent 14 years

(Cl. D62—3)

To all whom it may concern:

Be it known that I, Thomas V. Early, a citizen of the United States, residing at the city of Baltimore, in the State of Maryland, have invented a new, original, and ornamental Design for a Chimney-Cowl, of which the following is a specification, reference being had to the accompanying drawing, forming part thereof.

Fig. 1 is a side elevational view of a chimney-

cowl showing my new design; and Fig. 2 is an end elevational view taken from the right of Fig. 1.

The upright sides which are not shown in the drawing are substantially like the respective opposite sides that are shown.

I claim:

The ornamental design for a chimney-cowl, substantially as shown and described.

THOMAS V. EARLY.
